AUTOMOBILE

Richard A. Teague, Birmingham, Mich., assignor to Studebaker-Packard Corporation, Detroit, Mich., a corporation of Michigan

Application May 10, 1955, Serial No. 35,901

Term of patent 14 years

(Cl. D14—3)

FIG. 1

FIG. 2

FIG. 3

FIG. 4

Figure 1 is a front elevational view of an automobile embodying my new design;

Figure 2 is a fragmentary right perspective shown in reduced scale;

Figure 3 is a fragmentary left perspective thereof shown in reduced scale; and

Figure 4 is an enlarged fragmentary view of the mesh portion.

The dominant feature of my design resides in the full line portion of the drawing. The rear of the automobile is of conventional configuration.

I claim:

The ornamental design for an automobile, as shown and described.
